UNITED STATES PATENT OFFICE.

LOUIS KYSER AND ALFRED C. REX, OF PHILADELPHIA, PENNSYLVANIA.

DESIGN FOR A TOY SAVINGS-BANK.

Specification forming part of Design No. **11,358**, dated August 19, 1879; application filed June 24, 1879.
[Term of patent 3½ years.]

To all whom it may concern:

Be it known that we, LOUIS KYSER and ALFRED C. REX, both of Philadelphia, county of Philadelphia, and State of Pennsylvania, have invented an Improved Design for Toy Savings-Banks, of which the following is a specification.

Our invention relates to an improved design for toy savings-banks; and consists in making such a bank of two pieces, the upper part being a miniature bee-hive in shape, while the lower part is a base for same. These two parts are secured together, so as to be opened at will.

In the drawing is shown a perspective view of my improved design for a toy savings-bank.

A is a casting which represents a bee-hive in shape, and rests upon a base, B, also of cast-iron. The hive and octagonal base are firmly secured to each other.

The base is octagonal in shape, and has two ribs, F F, upon which it is cast, and which ribs

act as legs upon which the bank rests. On one side of casting A is a slot, E, through which the money is deposited.

The peculiarity of the design is a bee-hive having a slot in it, resting upon an octagonal base.

Our object is to make a strong and cheap toy bank.

We claim—

The design for a toy savings-bank, consisting of the representation of a bee-hive provided with a vertical slot near its top and resting on an octagonal base, substantially as described, and shown in the accompanying illustration.

In testimony of which invention we hereunto set our hands.

LOUIS KYSER.
ALFRED C. REX.
